PULL TAB FOR A REMOVABLE TEAR PORTION

Don B. Peters and George T. Powell, Dayton, Ohio, assignors, by mesne assignments, to Ermal C. Fraze, Dayton, Ohio

Continuation of design applications Ser. No. 10,526 and Ser. No. 10,527, Feb. 12, 1968. This application June 6, 1968, Ser. No. 12,692

Term of patent 14 years

Int. Cl. D9—02

U.S. Cl. D9—256

FIG. 1 is a perspective view of a pull tab for a removable tear portion embodying our new design;

FIG. 2 is a top plan view;

FIG. 3 is a side elevational view; and

FIG. 4 is an end elevational view looking from the left of FIG. 3;

FIG. 5 is a perspective view of another embodiment of our new design;

FIG. 6 is a top plan view;

FIG. 7 is a side elevational view; and

FIG. 8 is an end elevational view thereof taken from the left of FIG. 7.

This application is a continuation of our copending applications Ser. Nos. D. 10,526 and D. 10,527 both of which were filed Feb. 12, 1968.

We claim:

The ornamental design for a pull tab for a removable tear portion, substantially as shown and described.
